JESSE W. SIMPSON, OF ANDERSON, SOUTH CAROLINA, ASSIGNOR TO DRAPER CORPORATION, OF HOPEDALE, MASSACHUSETTS, A CORPORATION OF MAINE

FEELER MECHANISM FOR LOOMS

Application filed January 28, 1929. Serial No. 335,718.

This invention relates to feeler mechanisms for looms and is more particularly directed to feeler mechanisms of the side slipping type wherein the side slipping movement of the 5 feeler is utilized in effecting a change in the loom operation, as, for instance, replenishment of filling.

In feeler mechanisms of this general type the feeler is usually provided with filling engaging teeth to prevent side slipping movement of the feeler when a working supply of filling is in the shuttle on a detecting beat, and to permit such side slipping movement of the feeler when the filling has become substantially exhausted.

When a working supply of filling is in the shuttle the feeler is displaced frontwardly to a greater extent than it is when the filling approaches to or becomes substantially exhausted, with the result that the maximum tendency to cause side slipping movement of the feeler takes place when a working supply of filling is in the shuttle, and it happens at times under these conditions that the feeler 25 will side slip and call for a change of filling when a working supply is in the shuttle, and since the filling remaining on the ejected filling carrier or bobbin constitutes waste, this 30 improper action of feeler mechanism results in an abnormal loss of filling.

One of the objects of the present invention is to provide means whereby when the feeler is moved frontwardly by a working supply of filling on a detecting beat, replenishment of filling will be prevented, even though the feeler may side slip under the increased stress of the oncoming working supply of filling or the increase in spring acting means operating upon the feeler.

More specifically stated, the invention comprehends a side slipping feeler which may be of any usual type and provided with a transmitter actuator which is moved to an inoperative position when the feeler is moved 45 frontwardly by a working supply of filling in the shuttle on a detecting beat and remains in operative position to initiate replenishment of filling when the feeler detects approaching or substantial exhaustion 50 of filling in the shuttle.

The invention and novel features thereof will best be made clear from the following description and the accompanying drawings of one good practical form thereof.

In the drawings:

Fig. 1 is a perspective view showing a feeler mechanism provided with the present invention;

Fig. 2 is a front elevation of the feeler mechanism;

Fig. 3 is a plan view showing the feeler as being displaced frontwardly by a working supply of filling and by dotted lines indicating the relation of parts should the feeler side slip on the filling;

Fig. 4 is a similar plan view showing the relation of parts when the filling is substantially exhausted and the feeler partakes of its side slipping movement; and

Fig. 5 is a section on the line 5—5 of Fig. 4.

The feeler mechanism of the present invention may be advantageously employed in connection with filling replenishing mechanism whereby a new supply of filling is furnished when that in the active shuttle becomes substantially exhausted, but since the details of the filling replenishing mechanism form no part of the present invention and are now well understood by those skilled in the art, they are not herein shown and described, as they may be of any usual construction.

The loom frame has extending therefrom the usual shipper stand 1 with the projecting support 2 on which the feeler mechanism may be mounted, and in the present instance, a bracket 3 is secured to the support 2 by means of a bolt 4, as usual.

The feeler stand 5 may be of appropriate construction to support the operating parts of the feeler mechanism and as shown consists of a plate having a slot 6 through which passes the bolt 7 for adjustably securing the feeler stand in the desired operative position on the loom frame or bracket 3 secured thereto. The rear portion of the feeler stand 5 has an upstanding flange 8 provided with an opening 9 through which extends the feeler 10.

The feeler 10 may be variously contrived and may be constituted as a side slipping

feeler, but as herein shown as a good practical form, the feeler 10 is formed as a heavy wire or blade having its rear end portion 11 formed preferably with a bevel for engagement with a surface within the shuttle on detecting beats. The feeler 10 at its front portion is provided with a lateral extension 12 forming a stop for determining the rearward feeling position of the feeler, and co-operating with the extension 12 is a fulcrum stop 13 which may be constituted as a bolt or screw secured to the feeler stand 5.

In accordance with the present invention the feeler is provided with a transmitter actuator for operating the transmission mechanism to initiate filling replenishment when the filling in the shuttle has reached a predetermined degree of exhaustion, and such transmitter actuator may be varied in construction, but as herein indicated in the present instance of the invention where the feeler is formed of wire or a blade as described, the transmitter is constituted as a rearwardly extending finger 14 which may, as indicated, be formed by bending the front portion of the feeler, as at 12, and carrying the end thereof rearwardly, as at 14.

In this instance of the invention, the feeler is normally under the influence of a spring 30 which acts in a rearwardly inclined direction to move the feeler into its rearward feeling position, as indicated in Fig. 1, and to impart to the feeler a tendency to side slip when the feeler is moved frontwardly. As shown, the feeler stand 5 has secured thereto the bracket 15, to the end 16 of which is secured one end of a spring 17, the opposite end of the spring being secured at 18 to a bend in the rearwardly projecting transmitter actuator 14, and as will be apparent from Fig. 1, the spring 17 acts upon the feeler rearwardly of the fulcrum stop 13 when the feeler is in its rearward feeling position, but when the feeler is moved frontwardly the stress of the spring 17 is exerted on the feeler forward of the stop 13, as more clearly indicated in Figs. 3 and 4, with the result that the stress of the spring 17 then exerts a tendency on the feeler to side slip. Obviously, the further frontward the feeler is forced by a working supply of filling in the shuttle, the greater will be the spring stress imparted to the feeler for side slipping movement.

The present invention contemplates that side slipping movement of the feeler shall be utilized through the transmitter actuator to operate the transmitter for initiation of filling replenishment, and in the broad aspect of the invention the transmitter may be of any usual character.

As herein shown the transmitter comprises a slide 19 having an elongated slot 20 and preferably mounted beneath the feeler stand 5 by suitable means, such, for instance, as the threaded bolt 21 which may be passed through

an opening in the feeler stand 5 and through the slot 20 of the slide 19, with the head 22 of the bolt beneath the slide, as more clearly indicated in Fig. 5.

Where the construction employed for the transmitter is of the character described, the feeler stand 5 is provided with a laterally extending slot 23 through which extends a lug or projection 24 upon the slide 19, such projection constituting a member of the slide for engagement by the transmitter actuator which is operated by the feeler.

The transmitter slide 19 is connected to a link member 25 which forms part of a train of mechanism for initiating filling replenishment when the transmitter is moved laterally, to the right in the present instance.

The transmitter actuator as shown in the present instance and as above described is constituted by the backward extension or arm 14 which is offset from the main body of the feeler 10 to form an opening 26 into which extends the lug or projection 24 on the slide 19, the result being that should the feeler side slip as on substantial exhaustion of filling, Fig. 4, the slide 19 will be moved to initiate replenishment of filling and on backward movement of the lay the spring 17 will move the feeler rearwardly to its final feeling position, whereupon the feeler itself will act through the projection or lug 24 of the slide to return the transmitter to its initial position. Thus the transmitter is moved in the present instance of the invention positively in both directions, one to effect replenishment through the transmitter actuator, and the other to return the transmitter through the action of the feeler to its initial position.

From the construction described as an illustrated form of the invention it will be apparent that when the feeler is moved frontwardly by a working supply of filling in the shuttle, as indicated in Fig. 3, the transmitter actuator will likewise be moved frontwardly into an inoperative relation with the transmitter, and should the feeler at this time partake of its side slipping movement, as indicated by dotted lines in Fig. 3, the transmitter actuator will not operate the transmitter and consequently filling replenishment will not be effected, thereby obviating the waste that might occur should replenishment be effected with a working supply of filling in the shuttle.

As the filling becomes gradually depleted in the shuttle the feeler will be moved frontwardly a less and less amount until, when the filling has approached or reached substantial exhaustion, the transmitter actuator will not be moved into an inoperative relation with the transmitter, as indicated in Fig. 4, and upon side slipping movement of the feeler the transmitter actuator will operate the transmitter to effect replenishment of filling.

Since the filling is gradually exhausted

during the loom operation, it is expedient to form the rear end portion of the transmitter actuator 14 with an incline or bevel 27, and likewise, if desired, the projection or lug 24 of the slide 19 may be provided with an inclined front surface 28, as indicated, so that on rearward movement of the feeler these parts may pass each other without obstruction.

10 As indicated in the present instance of the invention, the fulcrum stop 13 may be conveniently located to engage the opening 26 between the transmitter actuator 14 and the main body of the feeler, and it will be noted 15 that during the movement of the feeler to and from feeling position the feeler will bear upon the fulcrum stop under the stress of the spring 17 and when the feeler partakes of its side slipping movement it will turn about 20 the fulcrum stop as a center.

The lay 29 and shuttle box 30 may be of usual construction, the latter to receive the shuttle 31 when it is in the detecting box, and the shuttle 31 may have its front wall 32 provided with the usual feeler opening 33 registering with a similar opening in the front wall of the shuttle box when the shuttle is in position for the action of the feeler. As usual, also, in shuttles of the replenishing 25 type, the filling carrier 34 has the filling 35 wound thereon and is detachably held in the replenishing shuttle by the bobbin holding jaws 36, as usual.

From the construction described as one 30 simple practical form of the present invention, it will be apparent that when the feeler is moved forwardly by a working supply of filling on a detecting beat, the transmitter actuator will be moved forwardly into an 35 inoperative relation with the transmitter, so that should the feeler side slip under such conditions filling replenishment will not be effected. When, however, the filling has become exhausted to a predetermined extent 40 and the feeler is consequently moved forwardly a less distance than when moved by a working supply of filling, the transmitter actuator will remain in operative relation with the transmitter to actuate the latter 45 when the feeler partakes of its side swipe movement and filling is substantially exhausted.

What is claimed is:

1. A feeler mechanism for looms, comprising, in combination, a feeler stand, a feeler mounted on the stand for frontward, rearward, and side slipping movements, a transmitter adapted to be actuated to initiate replenishment of filling upon side slipping movement of the feeler, a transmitter actuator carried by the feeler and moved forwardly beyond the transmitter when the feeler is moved forwardly by a working supply of filling on detecting beats that replenishment of filling may not be effected should the feeler

side slip along the working supply of filling, a fulcrum stop about which the feeler turns during its side slipping movement, and a spring acting upon the feeler rearwardly of the fulcrum stop in a direction to move the actuator 70 to its initial position when the feeler is in rearward feeling position and frontward of the fulcrum stop when the feeler is displaced frontwardly.

2. A feeler mechanism for looms, comprising, in its construction a feeler stand, a side slipping feeler directly mounted on the stand, a transmitter for initiating replenishment of filling having an engaging portion above the feeler stand, a transmitter actuator carried 75 by the feeler in spaced relation to the main portion of the feeler to receive said engaging portion therebetween and adapted to engage said portion of the transmitter on side slipping movement of the feeler when the filling is substantially exhausted on a detecting beat and for movement frontwardly out of engaging position with said portion of the transmitter when the feeler is moved frontwardly 80 by a working supply of filling.

3. A feeler mechanism for looms, comprising, in combination, a feeler stand, a feeler directly mounted on the stand for side slipping movement, a transmitter mounted for sliding movement beneath the feeler stand and having a lug extending through the feeler stand, a transmitter actuator carried by the feeler but disposed in spaced relation to the main portion of the feeler for receiving the lug therebetween to operate the transmitter and effect replenishment of filling only when the feeler fails to be moved frontwardly by a working supply of filling on a detecting beat.

4. In a feeler mechanism for looms, the combination of a feeler stand, a side slipping feeler carried by the feeler stand, a transmitter mounted for sliding movement and having a projecting lug, a transmitter actuator off-set to one side of the feeler forming an opening between the feeler and actuator into which the transmitter lug extends that the actuator may actuate the transmitter when the feeler side slips and the feeler may move the transmitter to its initial position when the feeler assumes its feeling position.

5. In a feeler mechanism for looms, the combination of a feeler stand having a feeler fulcrum, a floating side slipping feeler mounted on the feeler stand and provided with a looped rearwardly extending portion spaced from the main portion of the feeler to receive the fulcrum therebetween, a spring for moving the feeler rearwardly and longitudinally of the shuttle, a transmitter for initiating replenishment of filling, and the looped rearwardly extending portion of the feeler being of such length that it will actuate the transmitter when filling is substantially exhausted and the feeler side slips, but will not actuate

the transmitter when a substantial amount of filling is present and the feeler side slips.

6. In a feeler mechanism for looms, the combination of a feeler stand having a feeler fulcrum, a floating side slipping feeler mounted on the feeler stand and provided with a looped rearwardly extending portion spaced from the main portion of the feeler to receive the fulcrum therebetween, a spring for urging the feeler rearward and laterally, a transmitter for initiating replenishment of filling and provided with a part adapted to be engaged by the main portion of the feeler and shifted thereby to restore the transmitter to its normal position, and adapted to be engaged by the looped portion of the feeler and actuated thereby to replenish filling when the filling is substantially exhausted and the feeler side slips but not to be actuated thereby when a substantial amount of filling is present and the feeler side slips.

7. In a feeler mechanism for looms, the combination of a feeler stand having a feeler fulcrum, a floating side slipping feeler mounted on the feeler stand and provided with a looped rearwardly extending portion spaced from the main portion of the feeler to receive the fulcrum therebetween, a spring for urging the feeler rearward and laterally, a transmitter for initiating replenishment of filling and provided with a projection which lies between the looped rearwardly extending portion and main body portion of the feeler when the feeler is in its rearmost position and adapted to be engaged and shifted by the looped portion of the feeler when the filling is substantially exhausted and the feeler side slips but not to be engaged by said looped portion when a substantial amount of filling is present and the feeler side slips.

8. In a feeler mechanism for looms, the combination of a feeler stand having a feeler fulcrum, a side slipping feeler mounted on the stand for sliding and rocking movement relative to the fulcrum, an operating spring for the feeler having one end secured to the feeler and the other end anchored to act upon the feeler in a diagonal direction and adapted to move the feeler rearwardly and to rock it about the fulcrum, a transmitter for initiating replenishment of filling, a transmitter actuator upon the feeler for displacing the transmitter to initiate replenishment of filling when filling is substantially exhausted and the feeler side slips but arranged so as not to displace the transmitter when a substantial amount of filling is present and the feeler side slips, and said spring being adapted to exert a lateral pull upon the feeler in a direction to return the shifted transmitter to its normal position.

9. A feeler mechanism for looms, comprising in combination a feeler stand, a side slipping feeler mounted on the stand, a transmitter for initiating replenishment of filling and

having a feeler engaging portion, a transmitter actuator carried by the feeler and constructed to provide a recess to receive said portion and adapted to actuate the transmitter on side slipping movement of the feeler when the filling is substantially exhausted on a detecting beat and for movement frontwardly out of engaging relation with said portion when the feeler is moved frontwardly by a working supply of filling, and an operating spring for the feeler and arranged to exert a lateral pull upon the feeler in a direction to shift the transmitter to its normal position.

In testimony whereof, I have signed my name to this specification.

JESSE W. SIMPSON.
